UNITED STATES PATENT OFFICE.

FRANK A. GILB AND RICHARD ROOST, OF LOS ANGELES, CALIFORNIA.

ELECTRIC SWITCH FOR LAUNDRY MACHINES.

Application filed August 2, 1923. Serial No. 655,266.

To all whom it may concern:

Be it known that we, FRANK A. GILB and RICHARD ROOST, both residing at Los Angeles, in the county of Los Angeles and 5 State of California, have invented a new and useful Improvement in Electric Switches for Laundry Machines, of which the following is a specification.

In the operation of many types of machinery, and particularly in the operation of washing machines, it is necessary to cause an electric motor to operate through a pre-determined cycle. In the case of a washing machine, it is necessary that the motor revolve for a certain number of revolutions in a positive direction, and that the motor be then reversed, operating for a certain number of revolutions in a negative direction. This can be conveniently accomplished by the use of a motor operated switch, the motor of which runs at a constant speed, the switch being so constituted that the connections of the main motor driving the washing machine are changed 15 at regular intervals for the purpose of completing the desired cycle.

Our invention relates to a switch which is particularly adapted for use in this connection, or for use wherever frequent opening and closing of an electric circuit is necessary.

The principal object of the invention is to provide a switch of this character, which can be cheaply constructed and which is 35 very durable in operation.

A further object of the invention is to provide a switch which will have a quick break.

A still further object of the invention is 40 to provide a switch in which the parts liable to injury can be readily inspected and replaced.

Further objects will be made evident hereinafter.

45 Referring to the drawing which is for illustrative purposes only,

Fig. 1 is a plan of a portion of a washing machine switch embodying our invention.

50 Fig. 2 is an elevation partly in section of the same mechanism.

In the form of the invention shown, we provide a channel 11 which is preferably formed of insulating material, such as slate 55 or fibre. Mounted on the channel 11 are a plurality of bearings 12, in which an

operating shaft 13 is free to turn. The operating shaft 13 may be driven at a constant speed from an electric motor, or other source of power, not shown. Rigidly 60 mounted on the shaft 13 is a cam 14, having a release shoulder 15 and a block shoulder 16, the portion of the cam between these shoulders being called an application face 17.

Also mounted on the channel 11 is a primary standard 20, having a cylindrical hole therethrough in which a main tube 21 is free to slide. The main tube is provided with ears 22 at one end thereof, in which a pin 23 is mounted. Turning freely on the pin 23 is a fibre roller 24, this roller being so placed that it is engaged by the cam 14. Formed inside the tube 21 are inwardly projecting leads 26, against which one end of a compression spring 27 is free to rest, the other end of this spring bearing against a pin 28 which is secured in the primary standard 20 and which projects through slots 29 in the main tube 21. Also mounted on the tube 21 is a carbon holder tube 30, this tube having a small screw 31 projecting into the slot 29. Mounted in the end of the carbon holder tube is a threaded stud 35 on which a copper contact 36 is screwed. Clamped against the end of the tube 30 by means of the copper contact 36 is a strip of flexible contact material 37. This is a strip hanging down in a free lobe 38 and being secured by a screw 39 to the primary 70 standard 20. Situated inside the tube 21 is a compression contact spring 40 which presses against an abutment 41 formed in the tube 21, and against the end of the tube 30.

Also secured on the channel 11 is a secondary standard 45 which carries a carbon block 46, which is secured therein by means of a clamp 47.

The operation of the invention is as follows:

The cam 14 being turned in a clockwise direction as indicated by the arrow, Fig. 2, this cam acts upon the roller 24 against the spring 27, the lifting surface 16 forcing the roller to the left and the application face 17 holding it to the left for the purpose of completing the circuit. This is accomplished by the contact of the member 36 on the member 46, the current then flowing from the primary standard 20 through the flexible strip 37 to the contact 36, from the contact 36 to the carbon block 46, and from

this block to the standard 45. This completion of the circuit may be utilized for controlling the washing machine, or for other purposes. The degree of movement of the 5 main tube 21, due to the contracture of the roller 24 by the cam 14 is sufficient to compress the spring 40 and provide a resilient contact between the members 36 and 46. This allows for irregularity or wear in the 10 members 36 and 46, and also assists in obtaining a quick break, as will hereinafter be explained.

As the cam 14 turns, the roller 24 leaves the application face 17, due to the receding 15 diameter of the cam, shown at 15. The spring 27 then forces the main tube 21 to the right, as shown in Fig. 2. Due to the fact that the spring 40 is initially compressed, the copper contact 36 is held against the carbon block 46 for a short period, during 20 which the tube 21 is moving to the right. Whenever the end of the slot 29 reaches the screw 31, any further extension of the spring 40 is rendered impossible, and the contact 36 25 must move with the tube 21. As the tube 21 is already moved a short distance, it is evident that the copper contact 36 is quickly separated from the carbon block 46, and a very quick break is obtained.

30 It will further be evident that the contacts 46 and 36 which are subject to wear, can be very readily replaced and that they are in a position where they can be readily inspected and repaired without replacement.

35 We claim as our invention:

1. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring inside said tube; an inwardly projecting lip formed inside said tube against which one end of said compression spring 40 abuts; a key fixed in said primary standard and extending through slots formed in said tube, the other end of said compression spring abutting against said key, said spring being so situated as to hold said roller 45 against said cam; a contact holder tube surrounding said main tube at the end of said main tube opposite said roller; a threaded stud projecting from said contact holder tube; a copper contact threaded on said threaded stud; a strip of flexible conducting material having one end clamped between said copper contact and the end of said contact holder tube, said strip of flexible conducting material extending in a free loop to said primary standard upon which the other end of said strip of flexible conducting material is secured; a compression contact spring inside said main tube; an abutment inside said main tube against which one end of said compression contact spring abuts, the other end of said compression contact spring abutting against said contact holder tube; screws secured in said contact holder tube 50 projecting into slots in said main tube; and a fixed carbon block situated in a position to be engaged by said copper contact.

55 60

65

the other end of said strip of flexible conducting material is secured; a compression contact spring inside said main tube; an abutment inside said main tube against which one end of said compression contact 70 spring abuts, the other end of said compression contact spring abutting against said contact holder tube; screws secured in said contact holder tube projecting into slots in said main tube; a secondary standard; and a carbon block carried in said secondary standard in a position to be engaged by said copper contact.

2. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring inside said tube; an inwardly projecting lip formed inside said tube against which one end of said compression spring abuts; a key fixed in said primary standard and extending through slots formed in said tube, the other end of said compression spring abutting against said key, said spring being so situated as to hold said roller against said cam; a contact holder tube surrounding said main tube at the end of said main tube opposite said roller; a threaded stud projecting from said contact holder tube; a copper contact threaded on said threaded stud; a strip of flexible conducting material having one end clamped between said copper contact and the end of said contact holder tube, said strip of flexible conducting material extending in a free loop to said primary standard upon which the other end of said strip of flexible conducting material is secured; a compression contact spring inside said main tube; an abutment inside said main tube against which one end of said compression contact spring abuts, the other end of said compression contact spring abutting against said contact holder tube; screws secured in said contact holder tube 95 projecting into slots in said main tube; and a fixed carbon block situated in a position to be engaged by said copper contact.

3. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring in-

- side said tube; an inwardly projecting lip formed inside said tube against which one end of said compression spring abuts; a key fixed in said primary standard and extending through slots formed in said tube, the other end of said compression spring abutting against said key, said spring being so situated as to hold said roller against said cam; a contact holder tube surrounding said main tube at the end of said main tube opposite said roller; a threaded stud projecting from said contact holder tube; a copper contact threaded on said threaded stud; a strip of flexible conducting material having one end clamped between said copper contact and the end of said contact holder tube, said strip of flexible conducting material extending in a free loop to said primary standard upon which the other end 20 of said strip of flexible conducting material is secured; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said carbon contact.
4. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring inside said tube; an inwardly projecting lip formed inside said tube against which one end of said compression spring abuts; a key fixed in said primary standard and extending through slots formed in said tube, the other end of said compression spring abutting against said key, said spring being so situated as to hold said roller against said cam; a contact holder tube surrounding said main tube at the end of said main tube opposite said roller; a threaded stud projecting from said contact holder tube; a copper contact threaded on said threaded stud; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said carbon contact.
5. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring inside said tube; an inwardly projecting lip formed inside said tube against which one end of said compression spring abuts; a key fixed in said primary standard and extending through slots formed in said tube, the other end of said compression spring abutting against said key, said spring being so situated as to hold said roller against said cam; a contact holder tube surrounding said main tube at the end of said main tube opposite said roller; a threaded stud projecting from said contact holder tube; a copper contact threaded on said threaded stud; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said carbon contact.
6. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said cam; a compression spring inside said tube; an inwardly projecting lip formed inside said tube against which one end of said compression spring abuts; a key fixed in said primary standard and extending through slots formed in said tube, the other end of said compression spring abutting against said key, said spring being so situated as to hold said roller against said cam; a copper contact holder; a copper contact fixed in said holder; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said carbon contact.

ing into slots in said main tube; and a fixed carbon block situated in a position to be engaged by said carbon contact.

7. A power operated electric switch comprising: a driving shaft; a fixed bearing in which said shaft is free to turn; a cam rigidly secured on said shaft; a fixed primary standard having a cylindrical opening therein; a main tube sliding freely in said opening; ears formed on one end of said tube; a pin carried by said ears; an insulating roller carried on said pin, said insulating roller contacting with and being actuated by said ears; resilient means for holding said roller against said cam; a copper contact holder; a copper contact fixed in said holder; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said carbon contact.

8. A power operated electric switch comprising: a driving shaft; a fixed bearing in which said shaft is free to turn; a cam rigidly secured on said shaft; a fixed primary standard having a cylindrical opening therein; a main tube sliding freely in said opening; a roller carried by said main tube in such a position that it can make contact with said cam; resilient means for holding said roller against said cam; a copper contact holder; a copper contact fixed in said holder; a resilient connection between said copper contact holder and said main tube; an abutment inside said main tube against which one end of said compression contact spring abuts, the other end of said compression contact spring abutting against said contact holder tube; screws secured in said contact holder tube projecting into slots in said main tube; and a fixed carbon block situated in a position to be engaged by said copper contact.

In testimony whereof, we have hereunto set our hands at Los Angeles, California, this 27th day of July, 1923.

FRANK A. GILB.
RICHARD ROOST.
